UNITED STATES PATENT OFFICE

146,343

DESIGN FOR A CHAIR OR SIMILAR ARTICLE

Dorothy Bitter, New York, N. Y.

Application January 16, 1946, Serial No. 125,582

Term of patent 7 years

(Cl. D15—1)

To all whom it may concern:

Be it known that I, Dorothy Bitter, a citizen of the United States, residing in the city of New York, Borough of Manhattan, in the county of New York and State of New York, have invented a new, original, and ornamental Design for a Chair or Similar Article, of which the following is a specification, reference being had to the accompanying drawing, constituting a part hereof.

The figure on the drawing is a perspective view of a chair or similar article showing my new design. The opposite side has substantially the same appearance as the side shown.

The characteristic features of the present design reside in the portions shown by means of full lines in the drawing.

I claim:

The ornamental design for a chair or similar article, substantially as shown and described.
DOROTHY BITTER.
